DESIGN FOR A DOOR LATCH

Salvatore Merendino, Pasadena, Calif., assignor to Lockheed Aircraft Corporation, Burbank, Calif.

Application December 7, 1945, Serial No. 124,467

Term of patent 14 years

(Cl. D50—5)

To all whom it may concern:

Be it known that I, Salvatore Merendino, a citizen of the United States, residing at Pasadena, in the county of Los Angeles and State of California, have invented a new, original, and ornamental Design for a Door Latch, of which the following is a specification, reference being had to the accompanying drawing, forming a part thereof.

I claim:
The ornamental design for a door latch, substantially as shown.

SALVATORE MERENDINO.
